UNITED STATES PATENT OFFICE.

ALFRED SIVERSON, OF COLLEGE POINT, NEW YORK.

DESIGN FOR A TILING.

No. 40,065.

Specification for Design.

Patented June 15, 1909.

Application filed March 23, 1909. Serial No. 485,355. Term of patent 14 years.

To all whom it may concern:

Be it known that I, ALFRED SIVERSON, a citizen of the United States, residing at College Point, county of Queens, city and State of New York, have invented a new, original, and ornamental Design for Tilings, of which the following is a specification, reference being had to the accompanying drawing, forming part thereof.

The figure is a plan view showing the design of the tiling.

I claim:

The ornamental design for tiling as shown.

ALFRED SIVERSON.
